UNITED STATES PATENT OFFICE

FRANK W. SWEARINGTON, OF GREENSBORO, NORTH CAROLINA, ASSIGNOR TO DRAPER CORPORATION, OF HOPEDALE, MASSACHUSETTS, A CORPORATION OF MAINE

MAT-UP-REMOVING MECHANISM FOR LOOMS

Application filed December 23, 1929. Serial No. 415,882.

This invention relates to means for preventing or removing a matted up condition of the warps in a loom as they pass to the harnesses or shed forming mechanism. Frequently the warps in a loom become overlapped, bunched or crossed or otherwise out of parallelism due to various conditions. Some of the warps may be stuck together in such a matted condition by reason of the starch or sizing with which they have been treated. Some of the warps may be interlocked in the matted condition by reason of the fibres protruding therefrom or knots therein. But in any event, if the warps are not in parallelism and at any point are thus matted together, such a condition must be prevented or removed before the warps pass through the heddles or the shed forming means.

20 The present invention has for its object to provide a simple, efficient and practical means for eliminating this matted condition of the warps.

The invention has for its further object to 25 provide a comb extending transversely of the loom and mounted to swing from a position beneath the shed upward and rearward through the shed to separate any matted warps.

30 The invention has for its further object to provide such a comb with means for intermittently swinging it from and to its position beneath the shed and preferably with the upward and rearward swinging movement 35 taking place during the closing of the shed when the warps are under a lessened tension.

These and other objects and features of the invention will appear more fully from the accompanying description and drawings and 40 will be particularly pointed out in the claims.

In the drawings:

Fig. 1 is a view in side elevation and in 45 vertical cross section looking toward the inside of the side frame of an ordinary type of loom, together with a preferred form of the invention embodied therein.

Fig. 2 is a plan view partially broken away of the comb construction shown in Fig. 1.

The invention obviously may be embodied 50 in various types of looms and consequently

the type of loom herein illustrated is simply for the purpose of exemplifying the use of a simple and preferred form of the present invention.

The loom illustrated is shown as comprising side frames 1, a main crank shaft 2 connected in the usual manner to operate the lay swords 3 journaled at 4 and supporting the lay 5. The sheet of warps 6 is shown as extending over the whip roll 7 at the rear of the loom through the detector mechanism 8 and thence through the harnesses 9 of the shed forming mechanism, thence through the reed 10 and over the usual take-up roll 11 to the cloth wind-up roll 12. The usual cam shaft 13 is shown and this cam shaft, according to the common practice, by mechanism not necessary to illustrate, is assumed to have one rotation for each two rotations of the main or crank shaft 2.

The comb in which the present invention is shown as embodied comprises a back shown as a shaft 14 journaled in the side frames 1 and extending transversely of the loom beneath the shed and in the rear of the shed forming mechanism or harnesses 9. In this shaft is set a plurality of teeth 15. These teeth should be made of thin metal blades or wire of substantial rigidity and closely spaced so that as many teeth as possible may be employed and still allow them to pass readily through the sheet of warps. These teeth are preferably of sufficient length to extend from the shaft 14 entirely through the shed when the shed is open and the comb is in a vertical position. These teeth also have the end faces 16 which face the shed rounded off, as shown in Fig. 1, so that they will not catch on the warps as the comb swings through the shed.

Means are provided for intermittently swinging the comb upward and rearward through the shed from a position such as shown in full lines in Fig. 1 where the comb stands beneath the shed to a position such as shown in dotted lines. Thus as the comb swings upward and rearward, the rounded end faces enable the teeth to pass in between and separate the warps. Preferably this swinging movement takes place during the

closing of the shed so that the main engagement of the comb with the warps is taking place when the warps are under a lessened tension. Preferably this upward and rearward swinging movement takes place throughout its major extent when the shed is practically closed and when the warps are in the position indicated by the dotted line in Fig. 1.

10 The comb therefore acts by this upward rearward swinging movement to separate the warps and remove the matted up condition. The gentle, even action of the comb will usually accomplish this without breakage of the warps, but if the matted condition is so serious as to result in the breakage of the warps, the detector mechanism will act to stop the loom and thus enable the condition to be removed by hand before the warps pass into the heddles.

15 A simple and effective means for thus swinging the comb so arranged as to give the upward and rearward swinging movement during a single pick and during that portion 25 of the pick or cycle of the loom when the shed is moving to closed position is also illustrated. For this purpose a spiral-like cam 17 is journalled at 18 in the loom frame rearward of the cam shaft 13. This cam has 30 secured thereto a ratchet wheel 19. The cam shaft 13 is provided with an eccentric 20 operating an eccentric strap 21 on which is pivotally mounted a pawl 22 cooperating with the ratchet wheel 19. A follower lever 35 23 is pivoted at 24 to the loom frame and carries at its free end a follower roll 25 riding on the periphery of the cam 17. This follower is held in contact with the cam by a suitable spring 26 connecting it to the loom 40 frame. A link 27 is pivotally connected at its lower end to the follower lever 23 and at its upper end to an arm 28 projecting from the shaft 14 of the comb. The cam 17 at the portion 29 of its periphery drops suddenly 45 from the high part to the low part of the cam and the timing and arrangement is such that the follower rides down this portion 29 during that portion of a pick when the shed is moving to its closed position and thus acts 50 to swing the comb upward and rearward from the position shown in full lines to the position shown in dotted lines in Fig. 1. The return movement of the comb to its position beneath the shed takes place gradually 55 during the remainder of the rotation of the cam 17 and may occupy a period of several picks.

There is thus presented a very simple and effective means intermittently but continuously acting upon the warp sheet to prevent or remove a matted up condition of the warps before they enter the shed-forming mechanism and such a construction may not only be embodied in new looms, but readily applied to 60 existing looms.

Having thus described the invention, what is claimed as new, and desired to be secured by Letters Patent, is:

1. A loom comprising shed forming mechanism, a comb extending transversely of the loom in the rear of the shed forming mechanism and mounted to swing from a position beneath the shed upward and rearward through the shed to separate matted warps, and means for intermittently swinging the comb from and to the said position during the weaving operation with the upward and rearward swinging movements taking place during the closing of the shed when the warps are under a lessened tension.

2. A loom comprising shed forming mechanism, a comb extending transversely of the loom in the rear of the shed forming mechanism and mounted to swing from a position beneath the shed upward and rearward through the shed to separate matted warps, and means for intermittently swinging the comb from and to the said position during the weaving operation with the upward and rearward swinging movements taking place during the closing of the shed when the warps are under a lessened tension and with the return movement of the comb taking place during a plurality of picks.

3. A loom comprising shed forming mechanism, a comb extending transversely of the loom in the rear of the shed forming mechanism and mounted to swing from a position beneath the shed upward and rearward through the shed to separate matted warps, a cam journalled in the loom frame, means for rotating the cam during the weaving operation, and a connection to the comb operated by the cam acting to swing the comb intermittently from and to the said position during the weaving operation.

4. A loom comprising the construction defined in claim 3, in which the means for rotating the said cam comprises a ratchet secured to the cam, the usual cam shaft in the loom, and a pawl operated from the said cam shaft and cooperating with the ratchet to rotate the same.

In testimony whereof, I have signed my name to this specification.

FRANK W. SWEARINGTON.
